UNITED STATES PATENT OFFICE

LOUIS OSKOW, OF BROOKLYN, NEW YORK, ASSIGNOR TO BARLO ENGINEERING CO. INC., OF LONG ISLAND CITY, NEW YORK, A CORPORATION

WINDING MECHANISM

Application filed June 3, 1930, Serial No. 459,052. Renewed April 11, 1933.

This invention relates to winding mechanism. It is directed to a creel mounting a plurality of bobbins from which threads are fed to the warp beam in the usual manner, and contemplates the provision of signal means for indicating the tearing or breaking of one or more threads passing to said beam and the particular bobbins from which said torn threads were unwound. The operator 10 may thus be quickly apprised of the fact that one or more of the threads are broken so that the further operation of the machinery may immediately be stopped and the broken threads mended, thus obviating the necessity 15 for reversing the operation to unravel a considerable length of the threads.

An object of this invention is to provide in mechanism of the character described, wherein the bobbins are mounted in rows, 20 means for indicating the row in which thread from one of the bobbins has broken, and means for indicating the particular bobbin in said row having the broken thread, and further master signal means for indicating when 25 any thread on the entire creel has broken.

In winding apparatus now in use, the warp beam to which the threads from the bobbins are fed, is usually stopped as soon as a break 30 of any of the threads is discovered and the rotation of said wheel reversed, to permit mending of the broken thread, thus causing slack of the threads often resulting in entanglement thereof, and usually difficult to unravel or undo. It is accordingly, a further 35 object of this invention to provide means for automatically stopping the rotation of the warp beam as soon as any thread has been broken, whereby entanglement of the threads is effectively prevented.

Another object of this invention is to provide in apparatus of the character described, 40 means for preventing operation of the signal means when the warp wheel is idle and the threads are not being unwound from the bobbins so that the signal system is only 45 operative when the warp beam rotates and the weaving machinery is in use, said means further being arranged for permitting the signal indicating the row having a bobbin, 50 with a broken thread to remain in signalling

condition even when the warp wheel has stopped rotating upon breakage of said thread, the signal indicating the particular bobbin with the broken thread likewise remaining in indicating position until returned 55 manually to normal position.

Still another object of this invention is to provide apparatus of the character described, which shall be comparatively simple and inexpensive in construction, positive in operation and practical and efficient to a high degree in use. 60

Other objects of this invention will in part 65 be obvious and in part hereinafter pointed out.

The invention accordingly consists in the features of construction, combinations of elements, and arrangement of parts which will be exemplified in the construction hereinafter described, and of which the scope of application 70 will be indicated in the following claims.

In the accompanying drawings, in which is shown one of the various possible illustrative embodiments of this invention, 75

Fig. 1 is a wiring diagram of the apparatus embodying my invention;

Fig. 2 is a side elevational view of a creel frame mounting a plurality of bobbins and provided with automatic signal means embodying the invention; 80

Fig. 3 is an enlarged detail view of my centrifugal switch mechanism;

Fig. 4 is a cross-sectional view taken on line 4-4 of Fig. 3; and showing the position 85 of the switch when the threads are unwinding;

Fig. 5 is a view similar to Fig. 4, but showing the position of the switch when a thread has broken; and 80

Fig. 6 is a modified construction of the centrifugal switch.

Referring now in detail to the drawings, 10 designates a metal creel mounting, as herein-after described, a plurality of bobbins 11 feeding thread to a rotating warp beam 12 usually mounted adjacent and above the creel. The creels now in use usually are constructed 15 for supporting a large number of bobbins arranged in a plurality of closely adjacent 100

rows. For the purpose of illustration only, four vertical rows having four bobbins in each row are shown herein, it being understood that the creel may be constructed with any number of rows having any desired number of bobbins in each row. The creel may be of any suitable metal frame construction as shown herein, comprises a lower horizontal base 14 fixedly supported in any suitable manner to the side or end walls 15 and a top horizontal cross bar or support 16. The bobbins may be supported on either a single backing member or vertical wall 17 or may be supported on vertical frame members interconnecting the base 14 with the top horizontal cross bar 16. For rotatably supporting the bobbins 11, there is provided a plurality of horizontal rods or pins 18 attached to the backing member 17 in any suitable manner and projecting forwardly therefrom. The pins 18 are preferably arranged in a number of vertical rows. Mounted on each of the rods 18 at a point thereon adjacent to and somewhat spaced from the backing member 17, as by spacers 17a, is a fixed bushing 20 made of electrically insulating material and comprising a tubular member 20a received on said rod and a vertical flange 20b adjacent the spacing member 17a. Mounted on the tubular portion 20a of the bushing 20 is a tubular metal sleeve 22 preferably made of coiled wire construction and having an arm 23 extending outwardly therefrom for the purpose hereinafter appearing.

Rotatably mounted on each of the rods 18 adjacent the bushing 20 is a centrifugal switch mechanism 24. Said mechanism 24 comprises a tubular metal sleeve 25 rotatably received on the fixed rod 18 and a disc 26 extending at right angles to the sleeve portion 25. Pivotaly mounted on the disc 26 as on pin 27 at an eccentric point on said disc, is an arm 28 comprising a plate portion 29 lying flat against the disc 26 and a portion 30 bent at right angles to said portion 29. The disc 26 is provided with an outwardly extending portion 31 adapted to limit the outward rotation of said arm 28 and with a second outwardly extending portion or lug 32 to which is attached one end of a small tension spring 33. The opposite end of the spring 33 is attached to a lug 34 extending outwardly from the plate portion 29 of said arm 28 whereby the spring 33 normally tends to rotate said arm 28 inwardly or toward the rod 18. Integrally formed with said plate portion 29 is a projection 35 extending at right angles therefrom and adapted to contact the sleeve 22 upon being rotated inwardly toward the rod 18 by tension spring 33.

It will now be noted that when the arm 28 contacts the sleeve 22, said sleeve which is mounted on the insulating bushing 20 is electrically connected to the rod 18 and

hence thru the backing plate 17 to the creel frame which serves as a ground for an electrical signal system, described hereinafter in greater detail.

The bobbin 11 from which the thread 37 unwinds and is fed to the warp beam 12, may be attached to the disc 26 for rotation therewith by means of interengagement of pins or lugs 38 integrally formed with the disc 26 and received within openings 39 formed in the end wall 40 of the bobbin 11 adjacent said disc.

It will now be noted that when the bobbin rotates in the direction of the arrow shown in Fig. 4, as the thread therefrom is being unwound by the rotating warp wheel, the switch mechanism 24 rotates with said bobbin and the arm 28 by reason of centrifugal force rotates or flies outwardly away from the rod and hence breaks contact between the projection 35 and the sleeve 22. In this manner, electrical connection between the sleeve 22 and the ground, is broken. It will be noted also that during rotation of the bobbin, air pressure against the portion 30 of arm 28 will aid in causing the said arm to fly outwardly to break the contact.

It will now be understood that each of the rods 18 is provided with switch mechanism 24 and the bobbin 11 and with the threads 37 unwinding from the bobbins, extend upwardly and over the roller 41 suitably supported at the top of the creel frame and to the rotating warp beam 12 in the well known manner. Rotation of the warp beam 12 obviously pulls the threads for unwinding the freely rotating bobbins during the winding operation. As long as the threads are being unwound and remain unbroken, the bobbins 11 will continue rotating and the arms 28 will remain in an outwardly swung position as shown at Fig. 4 and hence the electrical connection between the sleeve 22 and the ground will remain broken. However, when the thread 37 from any bobbin breaks, the speed of rotation of the bobbin from which said thread was unwinding will decrease and the bobbin will then gradually stop rotating. Upon decrease of the speed below a predetermined point necessary to maintain the arm 28 in the position shown in Fig. 4, the spring 33 will pull said arm into contact with the sleeve 22 for closing the switch.

It will now therefore be obvious that the switch mechanism 24 for any bobbin will be closed automatically upon the event of breakage of the thread leading from said bobbin. As shown in Fig. 6, the coil spring 33 may be replaced by a leaf spring 33a suitably interconnecting switch arm 28 and lug 32 and normally urging said arm toward the sleeve 22.

Signal means is provided for indicating which switch has been closed, in which row

a switch has been closed, and also when any switch on the entire creel has been closed. To this end there is a lamp 50 mounted adjacent each vertical row of bobbins, preferably fixed on the top cross member 16. Suitable electro-magnetic annunciators 51 of the type having a swinging plate adapted to drop upon energizing the magnet thereof, are provided for each bobbin, said annunciators and bobbins being correspondingly numbered. The wiring for the annunciators 51 and lamps 50 are illustrated by diagram shown, in Fig. 1 of the drawings.

Each annunciator is connected by wiring 66 to the arm 23 of the terminal 22 for the bobbin corresponding thereto. The annunciators 51 for each row are connected in parallel electric circuit to each other by wiring 51a and in series circuit with the lamp 50 for said row by wiring 52. The lamps 50 are connected in parallel with each other and in series with a suitable electric power source 53 by wiring 55. Said power source 53 is connected by wiring 56 to one terminal 57 of a switch, the other terminal 58 of which is connected by means of wiring 59 to the backing frame 10 which acts as a ground for the centrifugal switch mechanism 24. Thus, when the fixed spaced terminals 57, 58 are interconnected by the switch arm 105, herein-after described, the power source 53 is grounded to the backing member 10 and hence to each of the rods 18.

It will now be understood that when the thread from any bobbin has broken, the speed of rotation of said bobbin is decreased and the arm 28 of the switching mechanism for said bobbin contacts the sleeve 22 for completing the electrical circuit thru the annunciator corresponding to said bobbin and thru the lamp for the row in which said bobbin is located. The current may then pass from the electrical power source 53 thru wires 56 and 59, to the ground 10, thru the rod 18, switch arm 28, sleeve 22, and wire 66, thru the annunciator for energizing the electro-magnet thereof and causing the numbered plate to drop for indicating the bobbin with the broken thread. The current will also pass thru wiring 51a and 52 thru lamp 50 in the row for the bobbin with the broken thread and thru wiring 55 back to the power source 53 to complete the circuit. Thus, the lamp in the row having the bobbin with the broken thread will also be illuminated to indicate the row having the bobbin with the broken thread. Obviously, upon observing the signal indicating a broken thread, the operator may stop the operation of the warp beam in any suitable manner so that the broken thread may be mended.

Rotation of the warp beam 12 is usually controlled by a beam 70 which in any suitable manner operates a clutch (not shown) for clutching the warp wheel in or out with re-

spect to a suitable rotary member operated by motor means (not shown). Thus, when the beam 70 is in the downward position as shown in Fig. 1, the warp beam is clutched to its motor means and is hence being rotated. For retaining the beam 70 in position for operating the warp beam 12, there may be provided a member 75 pivoted at the lower end thereof to any fixed member such as the floor 76. Said member 75 is provided with a hook portion 77 adapted to engage a resilient projection 79 fixed to one end of the beam 70. Said member 75 is furthermore provided with an upstanding projection 80 having a curved or cammed surface 81 on the side thereof adjacent the projection 79. It will thus be seen that the projection 80 serves as the means for releasing the beam, the same being adapted to be engaged by the operator's foot, for disengaging the hook from the beam for declutching the warp wheel and stopping operation thereof. Upon moving the beam 70 downwardly to again cause rotation of the warp beam, the spring projection 79 contacts the curved surface 81 of member 75 for pivotally moving the latter to permit said movement of the beam. Compression spring 82 serves in the manner hereinafter appearing, to snap the member 75 back to its normal position after the beam 70 has been moved to its lowermost position.

Means is provided for automatically unhooking the member 75 upon breaking of the thread on any of the bobbins so that rotation of the warp wheel may be automatically stopped as soon as any thread is broken and thus obviating the necessity for reversing direction of rotation of the warp beam as is usually necessary with winding apparatus now in use for mending the broken thread. To this end there is interposed in said wiring 56 an electro-magnet 90 adapted to attract when energized a switch arm 91 having thereon a contact member 92. When the arm 91 is attracted by the magnet 90 the contact 92 is adapted to contact a fixed terminal 93 connected by wiring 94 to a suitable power source 95. Said switch arm 91 is normally maintained out of contact with respect to said terminal 93 by any suitable means, such as spring 96. Said switch arm 91 is preferably made of electrical conducting material and is connected by wiring 97 to a relay 98, the latter being connected by wiring 99 to said power source 95 for completing the circuit.

It will now be seen that when the magnet 90 is energized, upon the breakage of any of the threads, the circuit thru relay 98 is automatically closed. Said relay 98 is adapted to actuate an armature 100 connected by arm 101 to the pivoted arm 75. The compression spring 82 for maintaining the switch arm 75 in normal hooking position shown

in Fig. 1, may be mounted on the armature 100 and is preferably interposed between the relay 93 and a flange 102 fixed to one end of said armature. Obviously, when the armature 100 is attracted it will compress the spring 82 and carry therewith the arm 75 for releasing the beam 70 which is then automatically lifted for declutching the warp beam and stopping rotation of the same. Hence, further unwinding of the threads is automatically stopped when any thread is broken and entanglement of threads usually resulting from reverse rotation of the warp beam to unravel the threads for mending, is obviated.

Means is provided for automatically cutting out the signal system except the lit lamp 50, simultaneously and automatically with the event of a broken thread and the stopping of the rotation of the warp beam so that the signal system is rendered inoperative whenever the warp beam is idle and the centrifugal switches drop into contact with terminals 22. To this end the switch arm 105 is connected to the beam 70 and is adapted to interconnect the terminals 57 and 58 only when the arm 70 is in its lowermost position shown in Fig. 1. When a thread has broken and the beam is caused to move upwardly, in the manner described above, for stopping the warp beam, the switch arm 105 will likewise be lifted to break the circuit thru the contacts 57, 58; and hence the electrical circuit thru the ground 10 and annunciators 51 will be broken.

It will be understood that once an annunciator has been energized by closure of the switch arm 28, the plate for said annunciator will drop and will remain in signal indicating position until moved upwardly manually in the well known manner. Thus, even though the power circuit thru the annunciators has been cut out, the annunciator which has been actuated by reason of the broken thread will remain in signalling position.

Means is provided however, for retaining the lamp in the row having the bobbin with the broken thread in signalling position even when the circuit thru the ground 10 and annunciators 51 has been broken. To this end the wire 52 leading to each lamp is directly connected as at 110 to an electro-magnetic core 111. A shunt 112 is coiled about the core 111 and is also connected directly to said core and to the wiring 52 as at 110. It will thus be seen that when any thread has broken and the centrifugal switch mechanism for the bobbin having the broken thread has been moved to closing position for completing the circuit thru the lamp 50, the shunt 112 which is connected in parallel to the lamp 50 will also receive current for magnetizing the core 111. Each core 111 is adapted to attach a switch arm 114 made of conducting material and adapted to directly contact the

core upon being attracted. Said switch arms 114 are interconnected by means of wiring 115 in parallel circuit and are further connected by wiring 116 in series circuit with said power supply 53. A master signal means 117, such as a lamp or the like, may be interposed in the wiring 116. A hand switch 118 may likewise be interposed between said wiring 116 for the purpose hereinafter appearing.

It will now be understood that when the thread of any bobbin has broken the core 111 in the row being said bobbin is energized for attracting the switch 114 and hence connecting the lamp 50 for said row in series with the power supply 53 by means of wiring 115, 116 and 55. Thus, although the switch 105 when moved upwardly with the beam 70 for declutching the warp beam upon the breakage of any of the threads as described above, will break the circuit thru the ground and prevent signalling of any of the remaining annunciators or lamps, the lamp 50 for the row having the bobbin with the broken thread will nevertheless remain illuminated for indicating to the operator which row has the broken thread. The annunciator for the bobbin having the broken thread will also indicate the bobbin corresponding thereto until the plate thereof is moved upwardly, as is well understood. With this construction therefor, although the warp beam is stopped automatically upon breakage of any thread and all of the bobbins hence stop rotation to permit closing movement of the switching arms 28, the signalling means nevertheless will not be actuated, by reason of the open circuit thru the ground 10.

It will now be understood that when any thread breaks, the annunciator corresponding thereto is actuated, the lamp therefor is illuminated, the warp beam is automatically stopped, the rest of the signalling system is deenergized, and the master lamp 117 is also illuminated. Obviously, the hand switch 118 must be closed during this operation.

For permitting opening of the switch arm 114, which has been moved to closing position, under the influence of the energized core 111, there is provided a circuit breaker 120 interposed in the wiring 55, preferably in the form of an ordinary push button switch which merely need be pressed once for completely deenergizing the entire signalling system.

When a broken thread has been mended, the beam 70 may again be moved downwardly toward the position shown in Fig. 1 to start rotation of the warp beam and hence unwinding of the bobbins which are thereby rotated for causing the switch arms 28 to fly outwardly. Preferably, the beam 70 upon being moved outwardly causes rotation of the warp beam 12 before the same is at its lowermost position so that the bobbins may be rotating

and the centrifugal switches open before the switch 105 closes the contacts 57, 58. With said construction, when the circuit thru the ground is closed by means of the switch 105, 5 the circuits thru the annunciators and lamps will be open until a thread breaks.

It will further be understood that when the relay 98 is energized upon breakage of a thread, the pivoted arm 75 is moved to the 10 right, looking at Fig. 1. Upon movement of the beam 70 however, upwardly to stop rotation of the warp wheel, the switch 105 breaks the circuit for electro-magnet 90 thus releasing switch arm 91 under influence 15 of spring 96. This action automatically de-energizes relay 98 and permits return of core 100 and hook arm 75 under influence of compression spring 82, back to the position shown in Fig. 1.

20 It will thus be seen that there is provided a device in which the several objects of this invention are achieved, and which is well adapted to meet the conditions of practical use.

25 As various possible embodiments might be made of the above invention, and as various changes might be made in the embodiment set forth, it is to be understood that all matter herein set forth or shown in the accompanying 30 drawings is to be interpreted as illustrative and not in a limiting sense.

Having thus described my invention, I claim as new and desire to secure by Letters Patent:

35 1. In combination with a creel, a plurality of bobbins mounted thereon, means for unwinding the threads from said bobbins, electrical signal devices associated with each bobbin, means for actuating one of said devices 40 for indicating which bobbin has a broken thread upon the event of breakage of one of said threads, and means for automatically rendering the remainder of said signal devices inoperative upon actuation of one of 45 said devices.

2. In combination with a creel, a plurality of bobbins mounted thereon, means for unwinding the threads from said bobbins, electrical signal devices associated with each bobbin, means for actuating one of said devices 50 for indicating which bobbin has a broken thread upon the event of breakage of one of said threads, means for automatically rendering the remainder of said signal devices inoperative upon actuation of one of said devices, and means for simultaneously and

automatically rendering said unwinding means inoperative.

3. In combination with a creel, a plurality of rows of bobbins mounted thereon, means for unwinding the threads for said bobbins, signal means for indicating the row having the bobbin with a broken thread, individual signal means associated with each bobbin for indicating the particular bobbin having the broken thread, means for rendering the unwinding means inoperative automatically upon breaking a thread, from one of said bobbins, means for simultaneously rendering said individual signal means for the remaining 70 of said bobbins inoperative.

4. In combination with a creel, a plurality of rows of bobbins mounted thereon, means for unwinding the threads for said bobbins, signal means for indicating the row having the bobbin with a broken thread, individual signal means associated with each bobbin for indicating the particular bobbin having the broken thread, means for rendering the unwinding means inoperative automatically 80 upon breaking a thread from one of said bobbins, means for simultaneously rendering said individual signal means for the remaining of said bobbins inoperative and means for retaining said signal means for said rows of bobbins in signalling condition, after said unwinding means has been rendered inoperative.

5. In combination with a creel, a plurality of rows of bobbins mounted thereon, means for unwinding the threads for said bobbins, signal means for indicating the row having the bobbin with a broken thread, individual signal means associated with each bobbin for indicating the particular bobbin having the broken thread, means for rendering the unwinding means inoperative automatically 100 upon breaking a thread from one of said bobbins and means for simultaneously rendering said individual signal means for the remainder of said bobbins inoperative, means for retaining said signal means for said rows of bobbins in signalling condition, after said unwinding means has been rendered inoperative, master signal means adapted to be energized when any thread from any of said bobbins tears and means for retaining said master signal means in signalling condition 105 upon rendering said unwinding means inoperative.

LOUIS OSKOW. 110
